FLOOR MAT WASHING MACHINE CASING

Nils I. Matson, Riverside, Ill., assignor to Jack Flapin,
Chicago, Ill.

Application April 27, 1959, Serial No. 55,669

Term of patent 14 years

(Cl. D49—1)

FIG. 1

FIG. 2

FIG. 4

FIG. 3

FIG. 4.

Fig. 1 is a front perspective view of the floor mat washing machine casing embodying my new design.

Fig. 2 is a right side elevational view thereof.

Fig. 3 is a top view thereof.

Fig. 4 is a vertical sectional view on a reduced scale taken through a portion of the casing in Fig. 1.

The rear of the casing (not shown) is substantially plain.

I claim:

The ornamental design for a floor mat washing machine casing, as shown and described.
